United States Patent Office

Des. 227,121
Patented June 5, 1973

227,121

FACSIMILE TRANSCEIVER APPARATUS

Larry D. Harrison, Clifton Springs, N.Y., assignor to
Xerox Corporation, Stamford, Conn.

Filed May 8, 1972, Ser. No. 251,578

Term of patent 14 years

Int. Cl. D14—03

U.S. Cl. D26—14 R

FIG. 1

FIG. 2

FIG. 3

FIG. 4

FIG. 5

FIG. 6

FIG. 1 is a front perspective view of a facsimile transceiver apparatus showing my new design;

FIG. 2 is a top plan view thereof;

FIG. 3 is an elevational view taken from the right side thereof;

FIG. 4 is an elevational view taken from the left side thereof;

FIG. 5 is a front elevational view thereof; and

FIG. 6 is a rear elevational view thereof.

I claim:

The ornamental design for a facsimile transceiver apparatus, as shown.
